UNITED STATES PATENT OFFICE

173,312

ROLLER FOR A PAINT ROLLER.

Stephen Knapp, Jr., Cleveland Heights, Ohio,
assignor to The Sherwin-Williams Company,
Cleveland, Ohio, a corporation of Ohio

Application August 2, 1954, Serial No. 31,700

Term of patent 14 years

(Cl. D9—2)

To all whom it may concern:

Be it known that I, Stephen Knapp, Jr., have invented a new, original, and ornamental Design for a Roller for a Paint Roller, of which the following is a specification, reference being had to the accompanying drawings, forming a part hereof.

In the annexed drawings:

Fig. 1 is a perspective view of a roller for a paint roller embodying the ornamental design.

Fig. 2 is a development of the roller showing the full surface of the roller shown in Fig. 1.

This application is a continuation-in-part of my copending applications Ser. Nos. D. 27,477 and D. 27,479, both filed November 6, 1953, and which are now abandoned.

I claim:

The ornamental design for a roller for a paint roller, substantially as shown and described.
